VALVE CAGE GRINDER

Niel Christensen, Shreveport, La., assignor to
Edward Benton Wilkey, Caddo Parish, La.

Application February 4, 1952, Serial No. 269,850

1 Claim. (Cl. 51—131)

This invention relates to a portable valve cage grinder and has for its primary object to rotate a valve cage in a closed path about a vertical axis while passing a rapidly rotating grinding wheel over the surface of the valve cage to be ground.

Another object is to facilitate the rapid loading and unloading of the turntable of the device between grinding operations so as to enable the grinding to be conducted with rapidity and with but a minimum loss of time when positioning a valve cage in the turntable preparatory to grinding, or removing a ground cage from the turntable.

Another object is to assure accurate grinding of the valve cage over the entire surface thereof.

The above and other objects may be attained by employing this invention which embodies among its features a turntable mounted to rotate about a vertical axis, a valve cage engaging center mounted adjacent the turntable for movement in a rectilinear path above the turntable from a position in axial alignment therewith to a position above the edge of said turntable, a grinding wheel mounted for movement in a horizontal arcuate path above the turntable from an active position adjacent the cage engaging center to an inactive position remote from said cage engaging center, means for rotating the turntable about its vertical axis, and means carried by the grinding wheel to rotate it about a vertical axis.

Other features include a speed reducing gear coupled to the turntable and to a suitable prime mover by which the speed of rotation of the turntable may be materially reduced over the speed of rotation of the drive shaft of the prime mover, and means mounted adjacent the turntable for supporting the grinding wheel in various adjusted positions relative to the axis of the turntable.

In the drawings,

Fig. 1 is a perspective view of a portable valve cage grinder embodying the features of this invention showing the parts in inactive position, and

Fig. 2 is a view similar to Fig. 1 showing the parts in active position and a hand power tool coupled to the grinding wheel for rotating it.

Referring to the drawings in detail an elongated substantially rectangular base 10 has mounted thereon adjacent one end a prime mover 12 the drive shaft 14 of which is equipped with a suitable clutch member 16. Mounted on the base 10 adjacent the end opposite the prime mover is a frame 18 carrying in vertically spaced relation to the base 10 a conventional speed reduction gear contained within a housing 20. The input shaft 22 of the speed reduction gear extends horizontally above the base 10 in axial alignment with the drive shaft 14 of the prime mover 12 and is equipped with a clutch member 24 which is adapted to cooperate with the clutch member 16 in establishing driving connection between the prime mover 12 and the speed reduction gearing contained in the housing 20. The output shaft of the speed reduction gearing extends vertically from the base 10 and has connected thereto for rotation therewith a shaft 26 which extends axially downwardly from a turntable 28

2

which rotates about the vertical axis of the output shaft of the speed reduction gearing. An upwardly extending annular flange 30 is carried by the turntable 28 adjacent the periphery thereof and forms in conjunction with the turntable a circular pocket 32 in which a valve cage C is received when being ground.

Secured to the base 10 intermediate the ends and to one side of the clutch members 16 and 24 is an upwardly extending post 34 which is provided adjacent its upper end with a horizontally extending stationary arm 36 having an elongated longitudinal slot 38 extending therethrough. The arm 36 extends above the turntable 28 toward the vertical axis about which the turntable rotates, and mounted for longitudinal sliding movement in the slot 38 is a valve cage engaging center 40 which is held in various adjusted positions on the arm 36 by clamp nuts 42. In its active position the center 40 is located directly above the center of the turntable 28 and in axial alignment with the vertical axis about which the turntable 28 rotates in order to hold a valve cage to be ground in proper relation to the turntable 28 during the grinding of the cage.

Mounted on the base 10 adjacent the end thereof remote from the prime mover 12 and extending vertically in parallel relation to the post 34 on the side of the turntable opposite the post is a standard 42' on which is mounted for vertical adjustment and rotation about its vertical axis a sleeve 44 carrying at its upper end a plate 46. A screw 45 is threadedly engaged through the upper end of the sleeve 44 and bears on the upper end of the post 42' for vertically adjusting said sleeve 44. Vertically spaced bolts 48 threadedly engage the plate 46 and extend through vertically spaced parallel horizontal slots 54 formed in an arm 52 which extends laterally from the plate 46 and carries at its end remote from said plate a bearing 56 in which is mounted for rotation about a vertical axis a grinding wheel 58. The grinding wheel is mounted on a shaft 60 which extends vertically through the bearing 56 and is provided at its end remote from the grinding wheel 58 with a socket 62 having flat sides for the reception of a flat sided drive shaft 64 of a conventional portable power tool 66. As illustrated in the drawings, the grinding wheel 58 extends below the bearing member 56 and arm 52 for movement in a horizontal arcuate path from an active position adjacent the axis of the turntable 28 (Fig. 2) to an inactive position remote from the turntable (Fig. 1). The horizontal arcuate path in which the grinding wheel 58 moves is located above the upper edge of the upstanding flange 30 of the turntable 28 so that when a valve cage C is in place in the turntable as illustrated in Fig. 2 the bottom surface of the grinding wheel 58 will contact the top surface of the cage C.

In use, assuming that the parts are in the position illustrated in Fig. 1 preparatory to mounting the cage C in the turntable 28, it is evident that the turntable will be clear so that the cage C may be deposited in the space 32 defined by the annular flange 30. With the cage C thus deposited, the cage engaging center 40 is moved longitudinally through the slot 38 in the arm 36 until it aligns with the axis of the turntable 28 at which time it is adjusted by one's turning the nuts 42 to bring its lower pointed end into contact with the stem S carried by the valve cage C. Thus the center 40 will serve to hold the valve cage C in axial alignment with the axis of the turntable 28 so that when the latter is driven by engaging the clutch members 16 and 24, the cage will rotate in a closed path concentric with the vertical axis. With the cage C thus positioned, the grinding wheel 58 is moved in its arcuate path into an active position adjacent the vertical axis of the turntable 28 and upon coupling a portable power tool 66 to the shaft 60 through the medium of the socket 62, it will be evident that the grinding wheel

may be rapidly rotated against the surface of the cage C to be ground. By one's loosening the screws 48, the arm 52 may be adjusted horizontally to properly locate the grinding wheel with relation to the axis of the turntable 28 so that the cage C may be accurately ground throughout its entire top surface.

While in the foregoing there has been shown and described the preferred embodiment of this invention it is to be understood that minor changes in the details of construction, combination and arrangement of parts may be resorted to without departing from the spirit and scope of the invention as claimed.

What is claimed is:

A valve cage grinder comprising a base, a turntable mounted on said base for rotation in a horizontal plane about a vertical disposed axis, said turntable being shaped and adapted to receive and position a valve cage to be ground, a post extending upwardly from said base and having its axis disposed parallel to and on one side of the axis of the turntable, a horizontally disposed arm mounted on said post, a centering pin carried by said arm and adjustable horizontally and vertically with respect thereto, said centering pin being adapted to engage the axis of said valve cage so as to center it with respect to the axis of said turntable, a standard extending upwardly from said base and spaced slightly radially outwardly from the turntable and having its axis disposed parallel

to the axis of said turntable on the side thereof opposite said post, a grinding wheel mounted on said standard and movable in an arcuate horizontal path thereabout and adjustable horizontally thereon and adapted to engage said cage to be ground when in active position, a socket carried by the grinding wheel on the axis thereof for forming a readily detachable driving connection with the shaft of a power tool and power means for driving said turntable.
